United States Patent Office

Des. 209,775
Patented Jan. 2, 1968

209,775

NAVIGATION PLOTTER

Burton D. Baker, 1477 Mountain View Ave.,
Chico, Calif. 95926

Filed Dec. 16, 1966, Ser. No. 5,062

Term of patent 14 years

(Cl. D52—6)

FIG. 1.

FIG. 2.

FIG. 3.

FIG. 4.

FIGURE 1 is a top plan view of a navigation plotter showing my new design;

FIGURE 2 is an end elevational view thereof;

FIGURE 3 is a side elevational view thereof; and

FIGURE 4 is a bottom plan view thereof.

The essential features of the design reside in the full line portions of the drawing.

I claim:

The ornamental design for a navigation plotter, substantially as shown and described.
